UNITED STATES PATENT OFFICE.

JOHN F. O'CONNOR, OF CHICAGO, ILLINOIS, ASSIGNOR TO WILLIAM H. MINER, OF CHAZY, NEW YORK.

HAND-BRAKE.

1,369,534.

Specification of Letters Patent. Patented Feb. 22, 1921.

Application filed March 1, 1919. Serial No. 279,942.

To all whom it may concern:

Be it known that I, JOHN F. O'CONNOR, a citizen of the United States, residing at Chicago, in the county of Cook and State of Illinois, have invented a certain new and useful Improvement in Hand-Brakes, of which the following is a full, clear, concise, and exact description, reference being had to the accompanying drawings, forming a part 10 of this specification.

This invention relates to improvements in hand brakes.

In the operation of railway freight cars, considerable difficulty has heretofore been experienced in applying the hand brakes while the cars are being switched in the freight yards. As is well known, the cars are shunted on the various spur tracks and it is the brakeman's duty to operate the hand brakes 15 in such manner as to properly "spot" the car, or in other words, bring it to rest at the proper point. With the ordinary style of hand brake, the brakeman tightens the brake to what he believes to be the necessary degree 20 and it is often found that the brakes have been too rigidly applied thus causing the cars to be stopped prior to their reaching the intended point or spot. The ordinary brake 25 does not provide any means for releasing gradually the brake so that the brakeman 30 may ease off the brake when he finds that the car is being brought to rest too rapidly.

The object of my invention is to provide in a simple device which may be used in conjunction with the ordinary vertical staff 35 types of hand brakes for freight cars means whereby the brakeman can graduate the release of the brakes with a minimum of effort.

In the drawing forming a part of this 40 specification, Figure 1 is a part elevational view, part vertical section, of a portion of an end wall of a car and the vertical brake staff showing my improvements in connection therewith. Fig. 2 is an end elevational 45 view of the structure illustrated in Fig. 1. In Fig. 2 is also indicated the usual foot-controlled locking pawl employed with brake staffs of the vertical type. Fig. 3 is a horizontal, sectional view taken substantially on 50 the line 3-3 of Fig. 1. Fig. 4 is a hori-

zontal, sectional view taken substantially on the line 4-4 of Fig. 1.

In said drawing, 10 denotes a steel end wall of a car, 11 a vertical brake staff, 12 the usual platform upon which the brakeman stands, 55 13 a ratchet wheel rigid with the staff 11, and 14 a locking dog coöperable with the ratchet wheel 13 and adapted to be controlled by the brakeman's foot in the usual and well known manner.

In carrying out my improvements, I preferably employ the usual hand wheel 15 at the top of the brake staff for rotating the staff in the ordinary manner inasmuch as the brakemen are accustomed to this method 60 of operation. A short distance below the hand wheel and where it may be attached to the wall of the car, I provide a housing consisting of a lower shelf 16 and an upper cap 17, both parts being riveted or otherwise 65 suitably rigidly secured to the wall. The two elements 16 and 17 provide a chamber 18 shown in Figs. 1 and 4. On the staff 11 within the chamber 18, I provide a cast wheel A 70 loosely rotatably mounted on the upper end 75 of the round portion of the staff. Said wheel A is formed with a peripherally arranged set of ratchet teeth 19-19 with which is adapted to coöperate two teeth 20-20 of an escapement pawl lever 21 mounted on a pivot pin 80 22 preferably formed integral with the member 16. Said lever 21 has a handle 23 adapting it for manual operation, and the opening 24 of the lever 21 within which extends the pivot pin 22 is somewhat enlarged to permit 85 tilting of the lever 21 to the dotted position shown in Fig. 1 and for the purpose hereinafter described. The lever 21 and ratchet teeth 19 act in the manner of an ordinary escapement ratchet mechanism, the teeth 20 90 of the escapement lever being properly spaced for this purpose as will be understood. On its upper face, the casting A is provided with ratchet teeth indicated at 25. Coöperable with the ratchet teeth 25 are corresponding ratchet teeth 26 on the under face of a cast bushing 27 vertically slidably mounted on the squared section 111 of the staff. The weight of the cast sleeve 27 will be sufficient to normally hold it in engage- 95 100

ment with the ratchet teeth 25 of the casting A so that, in effect, the ratchet teeth 26 and 25 form a clutch. As evident from an inspection of Fig. 1, the members 16 and 17 forming the housing provide suitable bearings for the staff 11 and the casting 27, and the latter is permitted a vertical movement within the chamber 18 sufficient to permit the teeth 26 thereof to clear the teeth 25 of the casting A.

The operation is as follows: The brakeman applies the brake in the usual manner, that is, by rotating the hand wheel in a clockwise direction as viewed in Figs. 3 and 15 4. During this movement, the casting 27 can ride freely over the casting A inasmuch as the teeth 25 and 26 are so arranged as to permit this. When the brake has been applied sufficiently, the brakeman will kick in 20 the locking dog 14 in the usual manner. After this is done, if the brakeman perceives that it is necessary to release the brakes slightly, he does so by kicking out the locking dog 14 and controlling the oscillation 25 in a horizontal plane of the escapement lever 21. By oscillating the lever 21 the staff 11 can be released in a counterclockwise direction one tooth 19 at a time and this is accomplished because of the clutch engagement 30 effected between the ratchet teeth 25 and 26. If the brakeman desires to release the brakes entirely, he depresses the handle 23 of the escapement lever 21 to the position shown in dotted lines in Fig. 1, during 35 which action the inner end of the lever 21 engages the under side of the casting 27 and lifts it to the dotted position shown in Fig. 1 until it is out of engagement with the ratchet teeth 25. When this has been 40 done, it is evident that the staff 11 is free to rotate in an unwinding direction.

The arrangement which I have provided is not only relatively inexpensive but may be easily applied to vertical brake staffs of 45 the most common form of hand brakes now employed on freight cars and gives the brakeman greater control over the setting of the brakes than has heretofore been possible. It will also be noted that during the 50 application of the brakes, the brakeman is not required to give attention to any more parts than he does with the present form of brakes and my improved escapement mechanism requires manipulation only during 55 the graduated release action.

I claim:

1. In a brake of the character described, the combination with an element having means associated therewith for directly effecting rotation thereof to tighten a flexible connection, of a ratchet wheel loosely rotatably mounted on said element, a pawl lever co-operable with said ratchet wheel; a second member non-rotatably mounted on 60 said element but adapted for movement

lengthwise thereof, said member and ratchet wheel having co-operating clutch-engaging faces, said lever being movable to an abnormal position to engage said member to shift the latter lengthwise of said element and thereby disengage the clutch faces of the member and ratchet wheel.

2. In a brake of the character described, the combination with an element adapted to be rotated to effect the winding of a flexible 75 connection; of a ratchet wheel loosely rotatably mounted with respect to said element; an escapement pawl lever pivotally mounted and co-operable with said ratchet wheel, said pawl lever having two spaced 80 teeth arranged to alternately engage with teeth of the ratchet wheel; and clutch mechanism interposed between said ratchet wheel and said rotatable element whereby said escapement pawl lever may be employed to control the rotation of said element in an unwinding direction, step by step.

3. In a brake of the character described, the combination with a vertical brake staff 90 and means for manually rotating the same, of a ratchet wheel loosely mounted on said staff, an escapement pawl lever co-operable with said ratchet wheel, a second member non-rotatably mounted on said staff but 95 adapted for longitudinal movement thereon, said member and ratchet wheel having clutch operating means, said escapement lever being movable to an abnormal position and adapted to disengage said clutch means.

4. In a brake of the character described, the combination with a brake staff having means for manually rotating the same, of a casting loosely rotatably mounted on said staff, said casting being provided with peripheral teeth and ratchet teeth on one of the faces thereof, an escapement pawl lever co-operable with said peripheral teeth of the casting, and a second casting non-rotatably mounted on the staff but adapted for longitudinal movement thereon, said casting having ratchet teeth co-operable with the ratchet teeth on the face of the first mentioned casting, said escapement lever being movable to a position to disengage the ratchet teeth 115 of said two castings.

5. In a brake of the character described, the combination with a vertical brake staff having a hand wheel at the top thereof for rotating the same, a housing through which the staff extends, said housing being adapted to be secured to an adjacent wall of the car, said staff having a circular section and a non-circular section within the housing, a casting loosely mounted on the circular 125 section of the staff and provided with peripheral teeth and face ratchet teeth, a second casting longitudinally slidably but non-rotatably mounted on the square section of the staff within the housing and provided 130

with ratchet teeth coöperable with the ratchet teeth of the first named casting, and an escapement pawl lever coöperable with the peripheral teeth of the first named casting, said pawl lever being adapted for pivotal movement in a horizontal plane and also in a vertical plane, movement of the

escapement lever in a vertical plane being adapted to effect disengagement of the ratchet teeth of said two castings. 10

In witness that I claim the foregoing I have hereunto subscribed my name this 21st day of Feb. 1919.

JOHN F. O'CONNOR.
